LIFTING JACK

Frank H. Schwerin, Bellevue Borough, Pa., assignor to The Duff-Norton Manufacturing Company, Pittsburgh, Pa., a corporation of Pennsylvania

Application January 12, 1931. Serial No. 508,127

10 Claims. (Cl. 280—53)

This invention relates to heavy lifting jacks having wheels onto the rolling support of which the jack can be tilted for trundling. These jacks have a firm base to rest on the ground, 5 and a standard rising from the base, in which standard the ram or lifting member is guided. Two wheels are applied to some lower part of the housing at such elevation that they normally clear the ground.

10 It requires a substantial amount of effort to pull one of these jacks over onto its wheels, and equally a considerable amount of resistance to restore the jack to its upright position, in addition to which there is action and reaction on the trundling handle when the weight, more or less balanced on the wheels, is wheeled about.

15 One of the objects of the invention is to provide a jack of this character with a trundling handle which is pivoted so that it can be folded down out of the way and which when erected is rigidly braced by and between the fixed parts 20 of a socket. The handle thus mounted can be latched in the erect position, the latch not being subjected to the stresses but being merely 25 a retainer.

Another object is to provide a trundling handle of a type easy to grasp, which handle when swung down can be disposed as close as possible to the housing.

30 The general purpose is to provide a light, compact, very strong and very convenient handle construction, which can be made easily and at little expense.

35 Other objects and features of the invention will be apparent to those skilled in the art as the specification proceeds.

In the accompanying drawing, forming part hereof:

40 Fig. 1 is an elevation of a jack embodying the invention, the handle being shown in the folded condition in full lines and in erect position in broken lines;

45 Fig. 2 is a fragmentary sectional elevation looking at right angles to Fig. 1, an intermediate portion of the handle being broken out;

Fig. 3 is a section taken on the line 3—3 of Fig. 1; and

50 Fig. 4 is a section taken on the line 4—4 of Fig. 2, two extreme positions of the handle in respect to swiveling about its longitudinal axis being shown in full and broken lines, respectively.

The housing of the jack has a base 2 and a 55 standard 3. In the latter is guided the ram, the head 4 of which is seen in Fig. 1. The lift-

ing screw and the operating mechanism need not be illustrated since they form no part of the invention. The jack may be operated by an air motor 5 applied to the lower part of the housing, though that is not material. 60

The two trundling wheels 6 are carried by axles 7 on suitable brackets 8 of the lower portion of the housing. It will be understood that these wheels are projected away from the base in what may be termed, for convenience, a 65 rearward direction, so that the jack can be tilted on the edge of the base as on a fulcrum until the slightly elevated wheels are brought into contact with the ground and the base is then raised clear of the ground, after which the 70 jack can be pushed along on the wheels. Provisions of this character are disclosed in the Kopf & Schwerin Patent No. 1,329,665, dated February 3, 1920.

The improved trundling handle will now be 75 described.

Bolted to the upper part of the standard, at the region which may be termed the back, is a fixture 9, which may incidentally cover an opening into the interior. This fixture is formed 80 to provide an integral socket 10 comprising an inner cheek 11, an outer cheek 12 and a side wall 13 uniting them, the whole preferably strengthened by a rib 14.

85 A pin 15 is held in openings in the lower portions of the cheeks, extending across the intervening recess. On this pin is pivoted one end of a handle stub 16. Because of the relationships, the axial projection of the pin 15 is substantially at right angles to the vertical plane 90 of the wheel axles 7, and the trundling handle will accordingly swing in a lateral arc. By this is meant that the handle folds down at one side of the jack considered as a wheeling body. In Fig. 1 it is shown inclining downward in front 95 of the left-hand wheel 6.

The remaining, and major, part of the trundling handle consists of a tubular shaft 17 having cross-bar grips 18 at its end. The shaft 17 is swiveled on the stub 16 so that the shaft can turn about its longitudinal axis relatively to the stub. A very economical way of producing this swivel connection is to fix a transverse pin 19 in the tube 17 where it takes over the stub 16, 100 and to form through the stub what may be termed a quarter-turn slot 20. The meaning of this term will be evident from the section shown in Fig. 4, where it will be seen that the solid portions 21 at the zone of the slot will 105 limit the pin 19, and therefore the shaft 17, to 110

a turning movement of 90° in either direction. Naturally the invention is not limited to the precise angular extent of this movability.

A spring-pressed latch bolt 22, having a handle knob 23, is guided in a boss 24 of the outer socket cheek 12, and the part of the handle shaft 17 which lies between the cheeks of the socket when the handle is erected has a hole 25 to receive the end of the bolt. The position of this hole in the circumference of the shaft 17 is such that when the handle is locked by the engagement of the bolt, the handle bars 18 are disposed transversely with relation to the direction of travel represented by the planes of the wheels 6.

When the handle is erected the latch not only locks the shaft 17 with its handle bars 18 against swiveling about the axis of the shaft, that is to say about the stub 16, but also locks the handle as a whole in the upright position.

When the latch is released the trundling handle can be swung down alongside the housing, free of the superstructure of the motor 5, if the jack is motor driven, and also clearing 25 the wheel at that side.

If it were not for the swivel in the handle, the end of one of the handle bars 18 would come into contact with some part of the housing, causing the handle to stand far out from the jack. That would make the cross-bar type of handle, which is most advantageous for the purpose of these jacks, impractical, and it is for that reason that I have provided a swivel in the handle, so that the handle bars can be turned to lie close to the jack in the folded or dropped condition. I have also provided a lock to keep the handle bars from swiveling when the handle is raised preparatory to moving the jack about, this being in addition to 30 the locking of the handle as a whole against swinging on the pivot 15.

When the handle is put up and locked, the operator grasps the bars 18 with both hands and pulls toward him. This upturns the jack on its base and brings the wheels to the ground, and it will be observed that, as between the handle and the jack, the stress of this effort is taken by the rigid socket 10, the cheeks of which are, so to speak, at right angles to the plane of action. The latch 22 is not called on to resist this strain or for any other duty than to latch or lock the handle against displacement. In like manner all stresses during trundling, and when the jack is let down again on 55 its base, are taken directly between the handle and the socket.

While the preferred embodiment of the invention has been described in detail it will be understood that the form of the invention may 60 be modified in various particulars.

I claim:

1. In a lifting jack having a base and housing comprising a standard, and a pair of wheels onto the rolling support of which the jack can be tilted; a socket fixed on the standard, said socket comprising outer and inner portions rigidly united in spaced relation, a pivot pin crossing the recess between said portions in substantially right-angular relation to the vertical plane through the wheel axles, and a trundling handle pivoted on said pin so that it can be swung up and down in a lateral arc, and when erected is rigidly braced between the outer and inner portions of said socket.

2. In a lifting jack having a base and housing

comprising a standard, and a pair of wheels onto the rolling support of which the jack can be tilted; a socket fixed on the standard, said socket comprising outer and inner portions rigidly united in spaced relation, a pivot pin crossing the recess between said portions in substantially right-angular relation to the vertical plane through the wheel axles, and a trundling handle pivoted on said pin so that it can be swung up and down in a lateral arc, and when erected is rigidly braced between the outer and inner portions of said socket, together with a latch in said socket adapted to hold the handle erect without being subjected to the strain of handling the jack.

3. In a lifting jack having a housing comprising a base and a standard, and a pair of wheels onto the rolling support of which the jack can be tilted; a trundling handle comprising a stub pivoted on the standard and a handle shaft swiveled on said stub, and a latch adapted to lock the handle in erect position and at the same time to lock the handle shaft against swiveling about its axis.

4. In a lifting jack having a housing comprising a base and a standard, and a pair of wheels onto the rolling support of which the jack can be tilted; a trundling handle comprising a stub pivoted on the standard and a handle shaft swiveled on said stub and provided with cross-bar grips, and means for locking the handle erect and the handle shaft against swiveling.

5. In a lifting jack having a housing comprising a base and a standard, and a pair of wheels onto the rolling support of which the jack can be tilted; a trundling handle comprising a part pivoted on the standard to swing into a folded position through a lateral arc substantially at right angles to the planes of rotation of the wheels, and a cross-bar grip part swiveled on the pivoted part.

6. In a lifting jack having a housing comprising a base and a standard, and a pair of wheels onto the rolling support of which the jack can be tilted; a trundling handle comprising a part pivoted on the standard to swing into a folded position through a lateral arc substantially at right angles to the planes of rotation of the wheels, a cross-bar grip part swiveled on the pivoted part, and means for locking both parts.

7. In a lifting jack having a housing comprising a base and a standard, and a pair of wheels onto the rolling support of which the jack can be tilted; a trundling handle comprising a stub pivoted to the standard for movement into a folded position, and provided with a quarter-turn slot at right angles to the longitudinal axis of the stub, a tubular handle shaft taking over the stub, and a cross-pin extending through said slot and connecting the handle to the stub so that the handle may be oscillated through a quarter turn with respect to the stub.

8. In a lifting jack having a housing comprising a base and a standard, and a pair of wheels onto the rolling support of which the jack can be tilted; a rigid socket fixed to the standard and having inner and outer cheeks, a pivot pin crossing the recess between said cheeks, a handle stub pivoted on said pin, a tubular cross-barred shaft taking over said stub between said cheeks, a swivel connection between said shaft and stub; and a latch on said socket to enter a hole in said shaft.

9. In a lifting jack having a housing comprising a base and a standard, and a pair of wheels onto the rolling support of which the jack can be tilted; a rigid socket fixed to the standard 5 and having inner and outer cheeks, a pivot pin crossing the recess between said cheeks, a handle stub pivoted on said pin and formed with a quarter-turn slot, a tubular handle shaft taking over said pin and formed with a quarter-turn 10 slot, a tubular handle shaft taking over said stub between said cheeks, a cross-pin in said shaft cooperating with said quarter-turn slot, and a latch on said socket to enter a hole in said shaft.

15 10. In a lifting jack having a base and hous-

ing comprising a standard, and a pair of wheels onto the rolling support of which the jack can be tilted; a bearing on the upper part of the standard with the axis of the bearing in a plane parallel to the plane of rotation of the wheels, 80 and a trundling handle journaled on the bearing, so that the handle can be swung from an erect position to a folded position through a lateral arc at right angles to the plane of rotation of the wheels, whereby the force applied to the handle to tilt the jack will be transmitted through the bearing to the standard and will not tend to move the handle into folded position. 85
